UNITED STATES PATENT OFFICE.

EARL P. OSWALD, OF DETROIT, MICHIGAN, ASSIGNOR, BY MESNE ASSIGNMENTS, TO THE HOOVER COMPANY, OF NORTH CANTON, OHIO, A CORPORATION OF OHIO.

ELECTROMAGNETIC SWITCH.

Application filed March 13, 1920. Serial No. 365,618.

This invention relates to electro-magnetic switches of the solenoid type, and the object is to provide a solenoid having an iron core which normally floats in mercury, energization of the magnet coil by a flow of electric current of predetermined amperage causing the core to become wholly or partially immersed raising the level of the mercury and thereby closing an electric circuit and a drop 5 in the amperage below the predetermined amount permitting the core to rise and the resulting fall in level of the mercury breaking the circuit. Another object of the invention is to provide a solenoid switch of 10 the character stated adapted to make or break a circuit through a mercury body upon energization or de-energization of the solenoid. A further object is to secure a construction simple and inexpensive in character 15 20 and to provide a switch mechanism having practically no liability whatever to become inoperative and further to provide a switch having no mechanically operated parts for making and breaking the circuit 25 30 to be controlled. Electro-magnets of the solenoid type have heretofore been utilized to move a switch arm into or out of contact with terminals of a circuit. Usually in such construction a spark passes from a terminal 35 to the switch arm on the breaking of the circuit preventing the use of such switch in the presence of an explosive gas for instance and due to the fact that switches of this character become readily corroded and be- 40 come practically inoperative through the adhesion of the mechanically movable parts with the contact members, such former construction is unadapted for use in places difficult of access as, for instance within a sealed chamber in which it may be necessary 45 to place the switch device. Therefore, an object of this invention as heretofore stated is to provide a construction in which such mechanically movable parts are eliminated 50 thereby avoiding the inefficiencies of such former construction and all liability of the device becoming inoperative through corrosion and to provide a construction avoiding the production of an electric arc exposed 55 to atmosphere thereby permitting the device to be used in the presence of an explosive gas or in the presence of a gas of a character that would corrode the usual contact members of an electric circuit. An additional object is to provide an electro-magnet of the

solenoid type in which the core member is practically immovable by influence of the current passing through the coil of the solenoid, the amperage of which is less than a predetermined amount. A further feature of construction consists in the provision of means whereby the core may be made to respond to the influence of current of a greater or a less amperage. These and other objects and the several novel features of the invention are hereinafter more fully described and claimed, and the preferred form of construction of an electro-magnet embodying my invention is shown in the accompanying drawings in which—

Fig. 1 is a cross section through the magnet taken on line 1—1 of Fig. 2.

Fig. 2 is a vertical section of the magnet taken on line 2—2 of Fig. 1.

Fig. 3 is a detail in section showing a mercury cell, the section being taken on line 3—3 of Fig. 1.

The device consists of a hollow body 1 formed of insulating material provided with an annular recess 2 to receive the coil 3, which coil is to be understood as being connected in an electric circuit. A chamber 4 is provided centrally in this body in which a soft iron core 5 of the solenoid may reciprocate. This central chamber 4 is provided with longitudinal grooves 6 the faces of which are open to the chamber. There are four of such grooves shown and the core 5 very closely fits the walls of the chamber between the said grooves 6 being sufficiently close to prevent a flow of mercury between the wall and core from one of the wells to the other around the core and still permit the core to freely move in the chamber under influence of electric current passing through the coil.

Some of the grooves 6, as shown in Figs. 1 and 2, extend only about half the length of the body and there merge into an enlargement 7 as will be understood from the drawing particularly Fig. 3, which enlargement extends radially outwardly from the respective groove 6. At the bottom of the outer face of the said enlargement is provided a small pocket 8 providing a wall 9 between the groove 6 and the pocket. Each of the several pockets at the bottom have an electric terminal 10 extending through the wall of the body and in electrical contact with the body of mercury in the pocket. The

electric circuit to be controlled is to be connected with these terminals of which there may be one or more depending upon the character of circuit to be controlled. The 5 grooves and central chamber of the body are closed at the top by means of a cover plate 11 which may be sealed in position by shaping the cover to provide a groove in which a sealing substance 12 may be inserted. By this construction described the 10 interior of the body is completely sealed to atmosphere.

A particular use of this solenoid switch provided with the three terminals here 15 shown is disclosed in my pending application Serial No. 358,721, filed February 14, 1920, showing the device utilized as a motor control apparatus. The device, however, may be used in various ways wherever a 20 circuit is to be closed or opened as may be readily understood by those familiar with the art.

There is a body of mercury provided in the chamber 4 as shown particularly in Fig. 25 2 which body occupies the groove 6 at the lower end and the portion of the chamber directly beneath the core 5. This core is made hollow as shown so that it readily floats in the mercury and when immersed 30 through the flow of the necessary current through the coils 3 will, upon breaking of the circuit or upon a drop in amperage occurring below that sufficient to cause an immersion of the core, upon its release quickly 35 raise in the mercury to normal floating position. A solid iron core may be used but has been found somewhat sluggish in action but, by making the core hollow as stated, a greater buoyancy and rapidity of action of 40 the core is secured upon release from the influence of the current through the coil.

It will also be noted that, by making the core hollow as shown, and providing a 45 threaded plug 13 therefor, a greater or less buoyancy may be secured by varying the length of the plug. The purpose of this is to provide a core that, with a certain number of ampere turns in the coil 3 and thus of 50 definite magnetic influence, will respond only upon flow of current of certain amperage and thus the electro-magnet may be standard as to size and quantity of copper in the coil and be made to suit various conditions by varying the buoyancy of the core 55 so that the core will be drawn downward into the mercury under a greater or less magnetic influence.

The core is preferably of soft iron and 60 normally floats above the center of the coil 3 as shown in Fig. 2 so that the core, under the magnetic influence, tends to move downward to position centrally of the coil. This movement downward displaces the mercury below the core and causes mercury to rise 65 in the grooves 6, the quantity of mercury

and displacement of the core being such that the rise in the grooves 6 is sufficient to cause the same to flow over the walls 9 to contact with the bodies of mercury in the pockets 8 and thus all of the pockets and the terminals therein are placed in electrical contact through the body of mercury. A greater or less number of terminals may be utilized than is here shown, the arrangement shown being simply illustrative of the method of 70 providing terminals for one or more of the pockets and, depending upon the circuits to be controlled, a greater or less number of pockets may be provided without departing 75 from the spirit of this invention. 80

Evidently the core 5 will remain immersed, partially or wholly depending upon its length, and weight during the interval in which there is a flow of current through the coil 3 of an amperage sufficient to hold 85 the same in such position. Upon a breaking of the circuit through the coil 3 or a decrease in amperage of current below that needed to overcome the buoyancy of the core, the core 90 will rise and the circuit between the several terminals will be broken due to the fact that the fall of mercury resulting from the rise of the core in its chamber separates the main body of the mercury from that in the pockets and thus a quick break of the circuit is 95 secured due to the buoyancy of the core in the mercury.

It is to be understood that this device may be made of any size desired having any desired number of ampere turns in the coil 100 3 and corresponding size of core and mercury well. It is further to be noted that an electric spark will pass between the mercury in the pockets and the main body of the mercury as the same breaks across the dividing wall 9 and that no detrimental effect is produced by the spark for the reason that, although a slight amount of mercury may become vaporized the same will condense on the walls in the upper part of the 105 several grooves and thus is not lost. It is further to be observed that, by sealing the chambers to atmosphere, no detrimental oxidation of the mercury may take place inasmuch as the oxygen remaining in the upper part of the grooves and central chamber will be soon exhausted due to passage of the electric spark between the pockets and the main body of mercury. Thereafter no further oxidation may take place. If desired, the chamber may be filled with a gas 110 incapable of chemically combining with the 115 mercury.

In some instances the main body of mercury may be continually in electrical contact 120 with one terminal of the controlled circuit as indicated at 14 in Fig. 2, the other terminal of which would occupy a position similar to that of the terminal 10. However, I preferably provide the terminals of the 125 130

controlled circuit in the pockets above the normal level of the mercury body as heretofore described.

From the foregoing description it is evident that the device is simple and inexpensive in construction and is very efficient in operation which is a fault of former types of solenoid switches heretofore used in controlling an electric circuit. It is further to be noted that a solenoid of this type may be inserted directly in the controlled circuit even though the circuit be carrying current of a high amperage as there are no metal contact points or members which are liable to become fused and no mechanical parts that may stick or refuse to operate and further, due particularly to the fact that the electric spark occurring on the breaking of the controlled circuit is produced within a sealed chamber, the solenoid may be placed even in the presence of an explosive gas or one that is corrosive in effect. After the several parts have been assembled and the wires connected with the terminals, the whole device including the terminals and end of attached wires may be cast in a block of insulating material covering the terminals as suggested by dotted lines 60 in Fig. 2. When so insulated the solenoid switch may be placed in water or in the presence of any fluid that would ordinarily prevent operation of a solenoid of previous known types having movable switch elements.

Having thus fully described my invention, what I claim and desire to secure by Letters Patent of the United States is—

1. In a solenoid magnet, a body having a central chamber, a body of mercury in the chamber, a soft iron core sustained in normal position by the mercury, said core having a hollow longitudinal chamber, a threaded plug closing the chamber and adapted to be turned to a greater or less extent into the chamber to vary the buoyancy of the core, and a coil of a predetermined number of turns about the lower end of the body, the center of which is below the center of the core when in normal position, the buoyancy of the core determining the amperage of current required to actuate the same.

2. In an electro-magnet of the solenoid type, a body of insulating material having a central longitudinal chamber, a magnet coil provided about the lower end of the body and chamber therein, a series of pockets formed in the interior wall of the chamber, the pockets being open at the upper end to the central chamber, an electric terminal extending through the body into each pocket, a body of mercury in the said chamber, an

iron core having an internal chamber of variable volume therein whereby its buoyancy may be varied floating in the said mercury body, depression of the core through influence of the magnet coil causing the body of mercury to rise to overflow into the pockets electrically connecting the said terminals.

3. An electro-magnetic switch comprising a body of insulating material having a central longitudinal chamber, a body of mercury therein, an iron core of variable buoyancy reciprocable in the chamber sustained by the mercury, said core having a central closed chamber plug forming the closure therefor, the plug adjustable in the chamber for varying its volume, a series of pockets open at the upper end to the central chamber of the body and positioned about the interior wall, an electric terminal extending into each pocket, a magnet coil about the lower end of the body and chamber, depression of the iron core by influence of the magnet coils causing the body of mercury in the chamber to rise to the level of the pockets bringing all of the said terminals into electrical contact.

4. An electro-magnetic switch of the solenoid type comprising a body of insulating material having a central longitudinal chamber and grooves provided longitudinally of the chamber opening thereinto, the upper end of the grooves being of greater depth than the lower end providing a shoulder between the two parts, a pocket provided in the shoulder thereby providing a wall between the pocket and the lower part of the groove, an electrical terminal extending into the pocket, a body of the mercury in the pocket covering the terminal, and a body of mercury in the bottom of the chamber, a magnet coil about the lower end of the body and chamber, an iron core normally positioned by the mercury above the center of influence of the coil, energization of the coil to an extent sufficient to overcome buoyancy of the core causing the core to move downward and the level of mercury raised to contact with that in the pocket connecting the terminal with the main body of the mercury.

5. An electro-magnetic switch comprising a body having a central chamber, a body of mercury in the chamber, a soft iron core sustained in the mercury, means comprising a recess in the iron core and an adjustable closure for the recess to vary the buoyancy of the core and a solenoid, the energization of which causes the iron core to be actuated.

In testimony whereof, I sign this specification.

EARL P. OSWALD.
